ELECTRIC LIGHT FIXTURE

Filed May 13, 1929

UNITED STATES. PATENT OFFICE

HARRY U. SCHOCKETT, OF DENVER, COLORADO

ELECTRIC-LIGHT FIXTURE

Application filed May 13, 1929. Serial No. 362,533.

This invention relates to improvements in electrical fixtures of the type employing a chain and which are ordinarily referred to as "chain pendant fixtures".

5 In the present construction of fixtures of the type to which this invention relates, the upper end of the chain is usually secured to the canopy by means of a loop connected with the canopy by means of knurled nuts and the 10 entire weight of the fixture is therefore supported by the canopy. The canopy is secured to the outlet box or to the ceiling by means of screws. With a construction of this type the weight of the fixture must be supported 15 by the wires during installation and this makes it difficult for the workmen to splice the wires and to solder and tape them.

In fixtures of this type the lower end of the chain is also connected with the shade holder 20 by means of a cast loop to the lower end of which the lamp socket is connected. This permits no adjustments of the shade holder with respect to the lamp and therefore when lamps of different sizes and shapes are employed, the best results cannot be obtained as 25 the position of the shade cannot be adjusted with respect to the lamp.

It is the object of this invention to produce a pendant fixture of such construction that 30 both the canopy and the shade holder can be moved along the chain and fastened to the latter in any desired position.

It is another object of this invention to produce a pendant fixture of such construction 35 that the upper end of the chain can be connected with the outlet box before the wires are spliced and which can be secured to outlet boxes having fixture studs or to outlet boxes that have no fixture studs and no inwardly projecting ears as well as to outlet boxes provided with inwardly extending ears that have threaded openings for the reception of screws.

40 The above and other objects which may become apparent as the description proceeds are attained by means of a construction and an arrangement of parts that will now be described in detail, reference for this purpose 45 being had to the accompanying drawing in

which the preferred embodiment has been illustrated and in which:

Fig. 1 is a vertical section through one of my improved pendant fixtures; and

Fig. 2 is a section taken on line 2—2, Fig. 1. 55

In the drawing reference numeral 1 represents the plaster of a ceiling in which the outlet box 2 is embedded. The lath to which the plaster is applied, has not been shown. In the example illustrated, the outlet box is 60 of the shallow type which comes flush with the surface of the plaster, but can be of a deeper type if necessary as the depth of the outlet box is immaterial as far as this invention is concerned. In the illustration 65 given, the outlet box is provided with a threaded fixture stud 3, as well as with inwardly projecting ears 4 that are perforated and threaded for the reception of screws 5. A double ended cap 6 has been shown as 70 secured to the stud 3 and a bridge 7 has been shown as attached to the ears 4 by means of the screws 5. The chain which consists of a plurality of links 8 has its upper link connected to the lower end of a chain switch 9, the upper end of this switch is connected to a loop 10, which is provided with a threaded plug 11. Reducing bushings 12 are secured 75 to the plug 11, in the present construction two of these reducing bushings have been 80 shown, but the number of reducing bushings is immaterial as they are merely used for the purpose of permitting the use of a single size of cast loop with any size of cap. It is evident that where a fixture stud is employed, 85 the bridge can be dispensed with and where a bridge is employed, the fixture stud is unnecessary. As my invention does not relate to the particular means employed for securing the fixture to the outlet box, this will not 90 be described in further detail but the description will now be directed to that part of the fixture to which my invention relates. Instead of using a slide stem for holding the canopy 13 as is sometimes done, I secure the 95 latter to the chain in such a way that it can be moved longitudinally of the chain and fastened to the latter in any position desired.

The canopy can be of any ordinary design with the exception that at the lower end it 100

is provided with a hub 14 which may be cast from brass or any other suitable material and which is secured to the canopy in any manner desired. In the embodiment illustrated, the hub has been shown as attached to the canopy by solder but this is merely for the purpose of illustration and in actual practice some other method of joining this hub to the canopy will undoubtedly be used. 5 The hub has a cylindrical outer surface and is provided with a central cylindrical opening 15. The wall of opening 15 has four slots 16 which are located ninety degrees apart and are of such depth that the distance between the bottoms of diametrically located slots is equal to the outside dimension of the links 8, so that the chain will pass through the hub in the manner shown in Fig. 2. For the purpose of clamping the canopy to the 10 chain, I have provided the hub with two threaded openings that communicate with the correspondingly located slots and in which are located screws 16^a that can be rotated from the outside by means of a suitable screwdriver. These screws, when rotated in such a direction that they move inwardly will be made to engage the side of one of the links and clamp the canopy to the link, as shown in the drawing. For the purpose of preventing these screws from becoming lost, each screw has been provided with a head 17, which is located within the slot and therefore when they are unscrewed, the head will engage the 15 inside of the threaded opening and hold the screw against becoming withdrawn and lost. Where a chain switch like that indicated by numeral 9 is employed, the canopy is provided with a grommet 18 through which the pull chain 19 extends. This chain may have an 20 extension 20 that terminates in an ornamental pendant 21 that is located at such a height that it can be conveniently reached for the purpose of operating the switch.

The holder 22 is constructed in substantially the same manner as the canopy and the hub and means by which it is secured to the chain have therefore been designated by the same reference numerals as those used in Fig. 2. The canopy and the holder usually 25 differ in this respect that the holder has a cylindrical flange 23 that is provided with a plurality of screws 24 for engaging and holding the shade 25. It is evident that the holder 22 can be adjusted relative to the 30 socket 26 and that it is therefore possible to adjust the position of the shade with respect to the lamp so as to get the best results. The socket is connected with the lower end of the chain by means of a cast loop 27 of ordinary construction.

It is apparent from the above description that I have produced a pendant fixture of such construction that it can be readily attached to an outlet box and which will fit 35 any condition of wiring such as conduit or

knob and tube work and which can also be applied to outlet boxes of varying depth and of different diameters. The fixture is supported from the ceiling or from the outlet box and is not supported by the canopy which makes a stronger and more substantial construction and which results in a device that can be more readily installed. The installation of these fixtures requires no extra tools as an ordinary pair of pliers and a screwdriver are all the tools that are necessary during the installation, and the holder and the lamp can be readily adjusted to suit any condition. 70

Having described the invention what is claimed as new is:

1. A pendant fixture comprising, in combination, a chain, means for securing one end of the chain to a support, a canopy or the like slidably connected with the chain, said canopy having an opening in one end through which the chain passes, the wall of the opening having four grooves spaced ninety degrees apart, the two oppositely located grooves being adapted to form passageways for alternate links of the chain and the other pair of oppositely located grooves forming passageways for the other links, and screws extending through the wall of adjacent grooves, said screws being adapted 85 to engage the chain to hold the canopy against longitudinal movement thereon. 90

2. A canopy, or the like, adapted to be secured to a chain, and to be held against longitudinal movement therealong, comprising a hollow member provided at one end with a hub having an opening adapted to receive the chain, said opening having two pair of diametrically located grooves adapted to receive and to form a passage for alternate links of the chain, another pair of grooves located in a plane which makes an angle of substantially ninety degrees with the plane of the other pair of grooves, and clamping screws located in the hub, one screw for each pair of grooves, said screws serving as means for holding the canopy in a predetermined relation with respect to the chain. 105

3. A pendant fixture comprising, in combination, means for securing one end of the chain to a support, a canopy or the like slidably connected with the chain, said canopy having an opening in one end through which the chain passes, the wall of the opening having four grooves spaced ninety degrees apart, the two oppositely located grooves being adapted to form passageways for alternate links of the chain and the other pair of oppositely located grooves forming passageways for the other links, and means secured 115 to the canopy for engaging the chain to hold the canopy against longitudinal movement thereon. 120

In testimony whereof I affix my signature.
HARRY U. SCHOCKETT. 130
